UNITED STATES PATENT OFFICE.

WILLIAM H. MINER, OF CHAZY, NEW YORK.

DRAFT-RIGGING FOR RAILWAY-CARS.

1,174,265.

Specification of Letters Patent. Patented Mar. 7, 1916.

Application filed November 2, 1914. Serial No. 869,775.

To all whom it may concern:

Be it known that I, WILLIAM H. MINER, a citizen of the United States, residing at Chazy, in the county of Clinton and State 5 of New York, have invented a certain new and useful Improvement in Draft-Rigging for Railway-Cars, of which the following is a full, clear, concise, and exact description, reference being had to the accompanying drawings, forming a part of this 10 specification.

My invention relates to improvements in draft rigging for railway cars.

The object of my invention is to provide 15 a draft rigging for railway cars of simple construction and efficient operation.

In the drawings forming a part of this specification, Figure 1 is a central vertical longitudinal section partly in side elevation 20 of a draft rigging embodying my invention, and showing the normal position of the parts; Fig. 2 is a horizontal section taken on line 2—2 of Fig. 1, and partly in plan view, showing the position of the parts 25 in full buff; Fig. 3 is a cross section taken on line 3—3 of Fig. 1; Fig. 4 is a cross section taken on line 4—4 of Fig. 1; Fig. 5 is a side elevation partly in vertical longitudinal section, showing the outer face of one of 30 the draft members.

Referring to the drawings, the numerals 6—6 indicate center sills, those shown in the drawings being of the wooden type, to which are secured the draft members 7—7, 35 each of said draft members comprising a metal arm 8 having near its upper edge an out-turned horizontal flange 9 engaging the lower face 10 of a center sill, the said flange being secured thereto by a plurality of bolts 40 11 passing therethrough and vertically through the center sill to which it is secured. Each arm is also provided with an in-turned flange 12 which engages the lower flange 13 of a preferably channel-shaped plate 14 secured to the inner face of the center sill 45 preferably by means of the transverse bolts 15—15 passing therethrough. A draft gear 16 is mounted between the draft members, and includes a casing or shell 17, which shell 50 in preferably construction is U-shaped in cross section, and open along its upper side 18 intermediate the rear, preferably integral, plate 19 and the preferably integral transverse plate 20 connecting the sides of 55 the casing. The forwardly extended lateral

portions 22 of the shell are adapted to receive the draw-bar 23 between them, the draw-bar being provided with the usual transverse slot 24 to receive a coupler key 25, the key extending through elongated 60 slots 26 in the casing and passing at its ends through the elongated slots 27 provided in the draft arms. Intermediate its ends, the shell is also provided with the elongated slots 28 through which the 65 key 29 is transversely passed through the casing, the said key 29 extending at its ends through the elongated slots 30 provided in the draft members. A transversely perforated follower 31 is mounted upon the 70 key 29 within the casing, and is adapted to be engaged in normal position and in buffering action of the gear by the rear end 32 of the draw-bar 23. Compression resisting elements, preferably springs comprising an 75 outer coil 34 and an inner coil 35, are mounted within the casing, the springs being seated at their rear end against the plate 19 of the casing, and at their forward ends against the follower 31. 80

In assembling the parts of the draft rigging, the springs, or other suitable compression resisting members, are placed in the casing through the opening on the upper side thereof. The casing is provided near 85 its rear end with preferably integral, oppositely arranged, outwardly extended lugs 36—36, said lugs being adapted to be received within the longitudinally extended slots 37—37 in the draft arms. The said 90 slots are each preferably closed at their rear by the web 40, which with the spaced-apart depending web 41 forms an offset portion 42 in the recess 37, which offset portion 42 is adapted to receive the upwardly extended 95 lug 43 with which each member 36 is provided. The engagement of the lugs 43 within the offset portions 42 assists in preventing spreading of the draft members in the operation of the draft rigging. The longitudinally extended slots 37—37 are each closed underneath by a longitudinally extending supporting plate 45, the ends 46—46 of which enter laterally into the slots 47—47, 100 extending transversely of each draft member, preferably near the ends of the longitudinally extending slot 37 in the same draft member. For further security, the supporting plates 45 are held in position, and accidental lateral displacement prevented, by 110

means of the vertical bolts 48—48 which pass therethrough and through the adjacent web 49 of the draft arm. The draft arms in preferable construction abut at their rear 5 ends against the front face 50 of a channel tie member 51, and at their forward ends are secured to the end sill 52 by the vertical bolts 53, which are also employed to support the draw-bar carry-iron 54.

10 From the foregoing description, the operation of the draft rigging will be understood.

On forward movement of the draw-bar, the coupler key engages against the forward 15 ends of the slots 26 in the casing, thus drawing the casing forward, the key 29 being stopped against the forward ends of the slots 30 in the draft members and holding the follower 31 against forward movement, 20 between which follower and the rear end 19 of the casing 17 the springs 34 and 35 are compressed. The members 36 at the rear of the casing slide forwardly in the slots 37 during the forward movement of the draw- 25 bar.

On rearward movement of the draw-bar, the coupler key moves rearwardly in the 30 slots 26 in the casing and the slots 27 in the draft arms, the casing is stopped against 35 rearward movement through the abutment of the lugs 36 of the casing against the rear ends of the slots 37 in the draft members; the rear end of the draw-bar in its engagement against the follower 31 forces the said 40 follower rearwardly within the casing, the key 29 meanwhile sliding rearwardly in the slots 28 through the casing and the slots 30 in the draft members, thus compressing the springs within the casing between the follower 31 and the rear end of the casing.

It will be clear that in mounting the draft gear between the draft members, the plates 45 are removed, the shell lifted to its position between the draft members with the 45 lugs 36 thereon mounted in the slots 37, which are then closed by laterally sliding the plates 45 into position, closing the lower edge of each of the slots 37, and then placing the bolts 48 into position to secure the 50 plates 45 against accidental displacement.

I claim:—

1. In a draft rigging for railway cars, the combination with a draw-bar and draft members, of a casing mounted between the 55 draft members and directly connected to the draw-bar, and springs within the casing, the casing being provided along its upper side with an opening for the passage of the springs.

60 2. In a draft rigging for railway cars, the combination with draft members, draw-bar and gear casing connected with the draw-bar, of oppositely extending lugs rigidly secured to the casing, the draft members being 65 provided with longitudinally extended re-

cesses to receive said lugs, the latter being limited in their movements in both directions by the ends of said recesses.

3. In a draft rigging for railway cars, in combination, draft members, a draw-bar, a gear casing open at the top and slidably connected to the draw-bar, compression resisting members and follower within the casing, a key engaging the draft members and the follower to stop the compression resisting members on forward movement of the draw-bar, lugs rigidly connected with the casing, the draft members being provided with slots to receive said lugs to stop the compression resisting means on rearward movement of the draw-bar. 75 80

4. The combination in a railway car draft rigging, of draft members and a draft gear casing, said casing being provided with lugs having offset portions, the draft member being provided with longitudinally extending flanges adapted to engage said offset portions to prevent spreading of the draft members. 85

5. In a draft rigging for railway cars, the combination with draft members having longitudinally extending slots therein, of a draw bar, and a casing slidably connected to the draw bar, said casing having outwardly extending lugs at the sides thereof 95 100 slidably in said slots, said slots and lugs having angled engaging shoulders arranged to permit relative sliding movement and prevent lateral separation of the draft members.

6. In a draft rigging for railway cars, in combination, draft members, a draw-bar, a casing slidably connected to the draw-bar, springs within the casing, a follower in the casing engaging the front ends of the 105 springs, a key engaging the follower and slidably mounted in the draft members, lugs rigidly connected with the casing and extended from the sides thereof, and slots in said draft members in which said lugs are 110 slidably received, said lugs having offset portions, and the draft members being provided with flanges adapted to engage said offset portions to prevent spreading of the 115 draft members. 120

7. In a draft rigging for railway cars, the combination with draft members having longitudinally extending slots which open on their inner sides into the space between said draft members, said slots being substantially L shape in cross section, of a casing slidably mounted within said draft members, said casing having laterally extending lugs slidable within said slots, said lugs being also substantially L shape in cross section. 125

8. In a draft rigging for railway cars, draft members, a gear casing and interengaging, relatively slidably means on the draft arms and gear casing to prevent 130

spreading of the draft arms; said means being in engagement with each other during all movements of said casing.

9. In a draft rigging for railway cars, 5 the combination with draft members, a draw bar, a front follower, a gear casing slidable with respect to said draw bar, and a spring within said casing, said casing being open at the top, of means for limiting the move-

ments of said casing and preventing lateral 10 separation of the draft members, said means including shouldered lugs movable with the casing and slidable in slots formed in the draft members.

WILLIAM H. MINER.
